UNITED STATES PATENT OFFICE.

WILLIAM H. HART, JR., OF PHILADELPHIA, PENNSYLVANIA.

MAILING-ENVELOP.

1,160,600.

Specification of Letters Patent. Patented Nov. 16, 1915.

Application filed April 14, 1915. Serial No. 21,350.

To all whom it may concern:

Be it known that I, WILLIAM H. HART, JR., a citizen of the United States, residing in the city and county of Philadelphia, State 5 of Pennsylvania, have invented a new and useful Mailing-Envelop, of which the following is a specification.

My invention consists of a mailing envelop or package whose closing flap is provided 10 with a supplementary flap which is adapted to be attached to the back of the envelop preferably by adhesive material, and is secured to said closing flap by a tongue thereon, the same being adapted to be reeved in 15 said supplementary flap, thus firmly connecting the latter with the closing flap.

The invention is satisfactorily illustrated in the accompanying drawing, but the important instrumentalities thereof may be varied, as long as they are included in the scope 20 of the claim.

Figure 1 represents a rear elevation of a mailing envelop embodying my invention the same being in closed position. Fig. 2 25 represents a view of a portion of the same in open condition. Fig. 3 represents a longitudinal section on the line $x-x$ Fig. 1. Fig. 4 represents an elevation of the closing flap of the envelop and the tongue thereon 30 on a reduced scale. Fig. 5 represents an elevation of the supplemental flap employed on a reduced scale. Figs. 6 and 9 represent rear elevations of other embodiments of the invention. Figs. 7 and 10 represent views 35 of portions of the envelops shown respectively in Figs. 6 and 9 in open position. Fig. 8 represents a longitudinal section on the line $y-y$ Fig. 6. Fig. 11 represents a longitudinal section on the line $z-z$ Fig. 9. 40 Similar numerals of reference indicate corresponding parts in the figures.

Referring to the drawings, 1 designates the body of a mailing envelop or wrapper, which excepting the feature of my invention 45 applied thereto is of usual construction.

Depending from the closing flap 2 thereof is the tongue 3, the same being integral with said flap.

4 designates a flap which is supplemental 50 to the flap 2 and having thereon on its inner face adhesive material as at 5, whereby it may be secured to the back 6 of the envelop, it being connectible with the flap 2. In said flap 4 are the openings 7, 8 and 9, 55 the opening 7 being near the top of the flap,

the opening 8 being near the bottom thereof, and the opening 9 being intermediate of the openings 7 and 8. The lower portion of the tongue 3 is inserted through the upper opening 7, thus placing the upper portion 60 of the flap 4 on the back of the flap 2. Then said tongue is passed under the flap 4 and inserted through the lower opening 8 when it is turned upon the cross bar 10 on the flap 4 formed by the openings 8 and 9 and 65 tucked into said opening 9 so that what was its lower portion is seated against the upper portion of the tongue and against the lower portion of the flap 2, whereby the tongue retains its position, and the flap 4 is reliably 70 connected with the flap 2. The envelop may now receive its merchandise or goods when it is closed and the flap secured to the back 6 of the body of the envelop by the adhesive material 5, when the envelop may be 75 mailed without liability of accidental opening, but the post office official may disengage the tongue 3 from the flap 4, when the flap 2 proper may be opened while the flap 4 remains a fixture of the body owing to its prior 80 attachment thereto by the adhesive material 5 employed and the contents of the envelop are exposed for inspection, after which the tongue may be reengaged with the flap 4 when the envelop is closed as before. 85

In order to open and raise the flap 2 in a convenient manner it is provided with the finger piece 11 cut or punched out of the material of said flap and remains integral therewith and capable of being moved out 90 so as to be grasped and drawn upwardly, the effect of which is evident.

In Figs. 6, 7 and 8, the supplemental flap has openings 7 and 8 therein, and the flap 2 has the opening 12 therein, whereby when the tongue has been inserted through said openings 7 and 8, it may be tucked into said opening 12, so as to be engaged with the latter.

In Figs. 9, 10 and 11, the construction is 100 similar to that shown in Figs. 1, 2, and 3, excepting that the finger piece 11 is dispensed with in the former.

While I have denominated the device as a mailing envelop, it may be used for general 105 business purposes as a package or folder to contain merchandise or goods, and carry or transmit the same in closed condition to its place of destination.

Having thus described my invention what 110

I claim as new and desire to secure by Letters Patent, is:—

In an envelop of the character stated composed of a body and a closing flap, a tongue which is continuous of said flap, a supplemental flap having therein a triplication of openings which are adapted to have said tongue reeved therethrough in opposite directions, the inner face of said supplemental

flap having adhesive material thereon adapting it to be secured to said body as a fixture thereof, leaving said tongue free for the opening of said closing flap without removal of said supplemental flap from the body. 10

WILLIAM H. HART, JR.
